CLAIM

The ornamental design for a toe separator, as shown and described.

DESCRIPTION

FIG. 1 is a left perspective view of the toe separator of the present design with an insert therein;

FIG. 2 is a right perspective view of the toe separator of the design of FIG. 1 without the insert therein;

FIG. 3 is a rear view of the toe separator of the design of FIG. 1;

FIG. 4 is a front view of the toe separator of the design of FIG. 1;

FIG. 5 is a left-side view of the toe separator of the design of FIG. 1; and,

FIG. 6 is a right-side view of the toe separator of the design of FIG. 1.

In the drawing, the broken lines show portions of a toe separator that form no part of the claim.
